(57) **CLAIM**

The ornamental design of a crosscut square, as shown and described.

DESCRIPTION

FIG. 1 is an isometric view of a first embodiment of a crosscut square in accordance with our new design;
FIG. 2 is a side elevation view thereof;
FIG. 3 is an opposite side elevation view thereof;
FIG. 4 is an end elevation view thereof;
FIG. 5 is an opposite end elevation view thereof;
FIG. 6 is a top plan view thereof;
FIG. 7 is a bottom plan view thereof;
FIG. 8 is an isometric view of a second embodiment of a crosscut square in accordance with our new design;
FIG. 9 is a side elevation view thereof;
FIG. 10 is an opposite side elevation view thereof;
FIG. 11 is an end elevation view thereof;
FIG. 12 is an opposite end elevation view thereof;
FIG. 13 is a top plan view thereof; and,
FIG. 14 is a bottom plan view thereof.
